(57) **CLAIM**

The ornamental design for the accessory for organizational system as shown and described.

DESCRIPTION

FIG. 1 is a perspective view of an accessory for organizational system showing a first embodiment of our new design in use;

FIG. 2 is a rear perspective view of the accessory for organizational system of FIG. 1;

FIG. 3 is another rear perspective view thereof;

FIG. 4 is a front view thereof;

FIG. 5 is a rear view thereof;

FIG. 6 is a top view thereof;

FIG. 7 is a bottom view thereof;

(Continued)

FIG. 8 is a left side view thereof;
 FIG. 9 is a right side view thereof;
 FIG. 10 is a cross-sectional view thereof taken along line 10-10 in FIG. 4;
 FIG. 11 is a perspective view of an accessory for organizational system showing a second embodiment of our new design in use;
 FIG. 12 is a rear perspective view of the accessory for organizational system of FIG. 11;
 FIG. 13 is another rear perspective view thereof;
 FIG. 14 is a front view thereof;
 FIG. 15 is a rear view thereof;
 FIG. 16 is a top view thereof;
 FIG. 17 is a bottom view thereof;
 FIG. 18 is a left side view thereof;
 FIG. 19 is a right side view thereof; and,
 FIG. 20 is a cross-sectional view thereof taken along line 20-20 in FIG. 14.

In the drawings, the evenly-spaced dashed lines depict portions of the article that form no part of the claimed design.
